UNITED STATES PATENT OFFICE

ALBERT SAGAR, OF SLATER, SOUTH CAROLINA

MOTION-TRANSMITTING DEVICE FOR LOOMS

Application filed September 12, 1930. Serial No. 481,548.

My invention relates to a motion transmitting device for operating a movable part of a loom.

The motion transmitting device may be connected with the lay sword of a loom, for moving the same, and will produce a much greater retardation or dwell of the lay sword at both front and back centre of the movement of the lay sword. The motion transmitting device is adjustable, for producing the desired dwell. The arrangement allows of the use of a larger shuttle or smaller shed at back centre. It also affords more time in which to change the bobbin, shuttle, or box, etc., at front centre, with a consequent increase in speed, with the result that improved weaving is obtainable.

The motion transmitting device is also adapted for connection with the rocker arm 20 of a dobby head. The use of the device in connection with the dobby head eliminates the shed closing upon the shuttle before it is clear, and also opens the shed before the shuttle enters, giving the top and bottom latches of the dobby head more time in which to connect or disconnect with the knives.

In the accompanying drawings, forming a part of this specification, and in which like numerals are employed to designate like parts throughout the same,

Figure 1 is a plan view of the motion transmitting device, showing the same connection with the lay sword of the loom,

Figure 2 is a side elevation of the same, showing the cranks in the rear position,

Figure 3 is a perspective view of the crank shaft, parts broken away,

Figure 4 is a side elevation of the device, showing the cranks in the raised position,

Figure 5 is a similar view, showing the cranks in the forward position,

Figure 6 is a similar view, showing the cranks in the lowered position,

Figure 7 is a side elevation of the motion transmitting device embodying my invention, connected with the rocker-arm of a dobby head, the eccentric pins being in the central position between the highest and lowest positions,

Figure 8 is a similar view, with the eccentric pins in the uppermost position; and

Figure 9 is an end elevation of the cam shaft and associated elements.

In the drawings, wherein for the purpose 55 of illustration, are shown preferred embodiments of my invention, attention being called first to Figures 1 to 3, inclusive, the numeral 10 designates the lay sword of a loom, having a bracket 11 rigidly secured thereto, as shown. 60

The motion transmitting device embodies a horizontally arranged crank shaft 12, driven by any suitable means. This crank shaft has a pair of cranks 13 and 14, crank 13 being the same length as crank 14, and both cranks extending radially in the same direction, and being radially angularly disposed. Crank 13 carries an eccentric pin 15, and the crank 14 carries an eccentric pin 16, the inner ends of these pins being rigidly connected by a crank 70 17, extending transversely of the cranks 13 and 14. The pins 15 and 16 are both eccentric with relation to the axis of rotation of the crank shaft 12, both disposed upon the same side of the crank shaft, and spaced the same 75 distances from the axis of rotation of the crank shaft. The cranks 13 and 14 and their pins 15 and 16 are arranged at an oblique angle, as more clearly illustrated in Figure 2.

A pitman arm 18 is pivotally connected 80 with the eccentric pin 15 and a pitman arm 19 is pivotally connected with the pin 16. The pitman arm 18 is pivotally connected with the upper end of a link 20, by means of a pin 21, and the pitman arm 19 is pivotally 85 connected with the lower end of the link 20, by means of a pin 22, this pivotal connection being, preferably, longitudinally adjustable upon the link 21, for regulating the dwell of the lay sword as it approaches the end of its stroke in either direction. The link 20 is pivoted at its center with the bracket 11, by means of a pivot or pin 23, and the pivots 21 and 22 are equi-distantly spaced from the 90 pivot 23.

In view of the foregoing description, it is obvious that as the crank shaft 12 rotates, the eccentric pins 15 and 16 turn with it, imparting longitudinal motion to the pitman arms 18 and 19. These pitman arms shift 100

the links 20 which causes the back and forth swinging motion of the lay sword. When the lay sword is shifted to the closed or open position, the link 20 is substantially vertically arranged, and further turning movement of the crank shaft will turn the link 20 upon its pivot before bodily shifting the same with the pitman arms, and it is this turning movement of the link upon its pivot 10 which produces the prolonged or pronounced dwell of the lay sword at the end of its stroke.

In Figures 7, 8 and 9, I have illustrated the motion transmitting device as connected 15 with the rocker arm of a dobby head, such as the rocker arm 12 in the dobby head, shown in United States Letters Patent No. 720,869, issued to H. Wyman, February 17, 1903. The invention is not restricted to the 20 use of the motion transmitting device in connection with any particular type of dobby head or rocker arm.

The numeral 24 designates the dobby arm mounted upon a rocker shaft 25. The rocker 25 arm 24 is provided with a longitudinal slot 26, as shown.

The numeral 27 designates a cam shaft, carrying a crank 28. An eccentric pin 29 is rigidly mounted upon the outer end of the 30 crank 28, and this eccentric pin has rigid connection with a circumferentially extending segment 30, having an eccentric pin 30' rigidly mounted thereon. The eccentric pins 29 and 30 are disposed at the same radial distance from the axis of rotation of the cam shaft 27, but these eccentric pins are circumferentially spaced. The pins 29 and 30 are also disposed at an oblique angle.

A coupling 31 is pivotally mounted upon 40 the eccentric pin 30' and a coupling 32 is pivotally mounted upon the eccentric pin 29. Pivotally connected with the coupling 31 by means of a pin 33, or the like, is a pitman rod or arm 34. A pitman arm or rod 35 is 45 pivotally connected with the coupling 32, as shown at 36.

The numeral 37 designates a link supported by a headed pin 38, arranged centrally thereof, and this pin is pivotally mounted 50 within the slot 26. A coupling element 39 is pivotally connected with one end of the link 37, by means of a pin 40 and this coupling element has pivotal connection at 41 with a co-acting coupling element 42, longitudinally adjustably mounted upon the upper end of the pitman arm or rod 34. A coupling element 43 is pivotally connected with the opposite end of the link 37, by means of a pin 44, and this coupling element is pivotally connected with a co-acting coupling element 45, by means of a pin 46. The coupling element 45 is longitudinally adjustably mounted upon the pitman rod or arm 35. The pivot pins 40 and 44 are equi-distantly 60 spaced from the pivot pin 38, and are pref-

erably longitudinally adjustable upon the link 37.

In view of the foregoing description, it is obvious that the rotation of the eccentric pins 29 and 30' will impart longitudinal movement of the pitman rods, or arms 34 and 35, bodily shifting the link 37, for swinging the rocker arm 24. When the rocker arm reaches the end of its stroke in either direction, the link 37 is generally horizontal and the initial 75 movement of the pitman arms or rods 34 imparts a turning movement of the link 37 upon its pivot, before bodily shifting the same, thus effecting the dwell of the rocker arm.

It is to be understood that the forms of my invention, herewith shown and described, are to be taken as preferred examples of the same, and that various changes in the shape, size and arrangement of parts, may be resorted to, without departing from the spirit 85 of my invention, or the scope of the subjoined claims.

Having thus described my invention, I 90 claim:

1. The combination with the movable element of a loom, of a link pivoted between its ends to said movable element, a crank shaft having eccentric pins disposed at an oblique angle, and pitman arms pivotally connected with the eccentric pins and with the link upon opposite sides of the pivot of the link.

2. The combination with the movable element of a loom, of a link pivoted between its ends with said movable elements, a crank shaft having eccentric pins disposed at an oblique angle, and pitman arms pivotally connected with the eccentric pins and with the ends of the link.

3. The combination with the lay sword of a loom, of a link pivoted between its ends with the lay sword, a crank shaft having eccentric pins spaced the same distances from its axis of rotation said pins being disposed at an oblique angle, pitman arms pivotally connected with the eccentric pins and pivotally connected with the link upon opposite sides of its pivot.

4. The combination with the lay sword of a loom, of a link pivoted between its ends with the lay sword, a crank shaft having eccentric pins disposed upon the same side of its axis of rotation and arranged the same distances from such axis said pins being disposed at an oblique angle, and pitman arms pivotally connected with the eccentric pins and with the ends of said link.

5. The combination with the rocker arm of a dobby head, of a link pivotally connected between its ends with the rocker arm, a crank shaft having eccentric pins disposed at an oblique angle, and pitman arms pivotally connected with the eccentric pins and with the link upon opposite sides of its pivot.

6. The combination with the rocker arm

of a dobby head, of a link pivoted between its ends with said arm, a crank shaft having eccentric pins which are disposed upon the same side of the axis of rotation of said shaft and arranged at an oblique angle, and pitman arms pivotally connected with the eccentric pins and with the end portions of said link.

7. The combination with the rocker arm of 10 a dobby head, of a link pivoted between its ends with said arm, a crank shaft having a crank, eccentric pins carried by the crank and circumferentially spaced and disposed at an oblique angle, and pitman arms pivotally connected with the eccentric pins and with the link upon opposite sides of its pivot.

8. The combination with the rocker arm 20 of a dobby head, of a link pivoted between its ends with said arm, a crank shaft having a radial crank, a circumferential segment disposed at the outer end of the crank, an eccentric pin connecting the segment and crank and disposed at an oblique angle, a second eccentric pin carried by the segment and 25 spaced from the first named pin, and pitman arms pivotally connected with the pins and with the link upon opposite sides of the pivot of said link.

In testimony whereof I affix my signature.

30 ALBERT SAGAR.
